UNITED STATES PATENT OFFICE.

WARREN D. WILLIAMS, OF ERIE, PENNSYLVANIA.

STEAM SHOVEL.

Application filed January 12, 1922. Serial No. 528,789.

To all whom it may concern:

Be it known that I, WARREN D. WILLIAMS, a citizen of the United States, residing at Erie, in the county of Erie and State of Pennsylvania, have invented certain new and useful Improvements in Steam Shovels; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to steam shovels and has for its object the providing of suitable mechanism for securing the dipper to the dipper-stick in such a manner that the dipper can be used to work towards the machine in 20 the manner of a hoe, or away from the machine in the manner of a shovel; thereby making the ordinary steam shovel apparatus adapted to be used in either manner.

The features of my invention are herein- 25 after fully set forth and pointed out and are illustrated in the accompanying drawings, in which:

30 Figure 1, is a side elevation of a steam shovel embodying my invention, part of the housing thereof being broken away.

Figure 2, is a side elevation of a fragment of the mechanism shown in Fig. 1, with the dipper reversed.

35 Figure 3, is an enlarged side elevation of my improved dipper mechanism.

Figure 4, is a rear elevation of the same.

Figure 5, is an edgewise view of the lower portion of the dipper-stick.

In these drawings A indicates the house 40 enclosing the power plant of the machine; B indicates the shovel boom, the lower end of which is pivoted by means of the pivot b upon the casting A' secured in the frame of the housing A; said boom being main- 45 tained in its proper position by means of stay rods B'. The boom B is constructed in the usual manner, of two parts spaced apart. Upon the boom B is secured the usual crowding engine C, which operates the usual 50 crowding pinion C'. D indicates the dipper-stick which is constructed in the usual manner, of two pieces, as shown in Figs. 4 and 5, and is provided with rack teeth d which intermesh with the crowding pinion C'; the 55 lower end of this dipper-stick is provided with a casting D' which has bifurcated arms

d' between which arms the pulley D² is placed for the purpose hereinafter explained.

On the outer face of this dipper-stick I place metal plates E E which are secured thereon by means of pins E' and E², the pin E² passing through the pulley D², and upon which said pulley revolves. The plates E are provided at the lower ends with lateral arms e e which have holes through their lower extremities. The upper ends of the plates E are provided with a plurality of holes e', by means of which the plates E E may be secured upon the dipper-stick at such angle as may be desired, by means of 70 the pin E². F indicates the dipper, upon the upper side of which is secured a metal plate F', which is provided with ears f at its four corners, through which ears holes f' are provided, which will co-incide with the 75 holes in the ends of the lateral arms e of the plates E.

The plate F' is also provided with an arm F², the end of which is bifurcated as shown in Fig. 4, to receive the looped end of a drag-line cable G, which is secured therein by means of a pin f²; and upon this pin f² is placed a bell crank lever H for operating the latch h of the dipper door H', one arm of said bell crank lever being connected with said latch by means of link h'; h² indicates a dumping cord secured to the bell crank lever H which extends thence to the housing A; J indicates a pin passing through the front ears f on the plate F' to secure the dipper to the front arms e of the plates E; K indicates straps pivoted upon the lower pin E', and to the upper ends of the straps K a block K' of the lifting tackle is secured, through which the lifting cable K² operates 95 over the pulley B' in the upper end of the boom B in the usual manner.

The drag-line cable G extends from the arm F² over the pulley D² in the dipper-stick and therefrom to the usual drum mechanism (not shown) in the power house A. In operation, when the dipper is lowered by the lifting cable K², and extended by the operation of the crowding engine C to the position shown by full lines in Fig. 1, power 100 is applied to the drag-line cable G which causes the dipper F to tip its operating edge down, and the continued strain on the cable G, (the lifting cable K² being slackened), draws the dipper F toward the machine; 105 when the dipper-stick has swung to a substantially perpendicular position the crowd-

ing engine is operated to lift the dipper upward, the drag-line being now slackened, and the slack in the lifting cable being taken up.

As the dipper is only secured to the plates 5 E at its front end, the gravity of the dipper, and the material in it cause the rear end of the dipper to swing below the plane of its front end, so that the material within the dipper will not be spilled out. The lifting 10 cable K² and the crowding engine C are now caused to co-operate to carry the dipper upward and outward so that the same can be swung to the desired position for dumping the dipper. This dumping operation can now 15 be accomplished by the shovel operator pulling the dumping cord h² thereby releasing the latch of the door H', or he can cause the slack in the drag-line G to be taken up, which will cause the dipper F to swing on the front 20 pin J thereby inverting the dipper and allowing the contents to spill out of the front end thereof.

Should it be desired to use this dipper to 25 operate away from the machine, the drag-line G is disconnected from the arm F², the dumping cord is disengaged from the bell crank lever H, the pin J is removed, and the dipper F thereby disengaged, is reversed and the pin J passed through the holes f' in the 30 ears of the plate F', and a pin J² passed through the ears f at the front end of the dipper F, so that the dipper F and dipper stick D are now in the position shown in Fig. 2, when the dumping cord h² can again 35 be attached to the bell crank lever H, as shown in Fig. 2.

From the foregoing it will be obvious that 40 by means of my invention the ordinary steam shovel can, within a few minutes, be changed into a steam hoe, by simply reversing the dipper on the dipper stick, and attaching thereto, in the manner described, a drag-line.

Having thus fully shown and described 45 my invention so that others may be enabled to utilize the same, I do not desire to be lim-

ited to the exact mechanism shown and described, as many modifications can be made therein without departing from the scope of my invention; therefore what I claim as new 50 and desire to secure by Letters Patent is:

1. In an apparatus of the class described, a dipper, a plurality of spaced ears having openings therethrough adjacent to the front and rear edges of the upper side of said 55 dipper, a dipper stick, plates secured on the lower end of said dipper stick, lateral arms extending from opposite edges of said plates and overlapping said ears on said dipper and having openings which coincide with the 60 openings in said ears, and pins through said openings in said ears and arms.

2. In an apparatus of the class described, a dipper-stick, a dipper, means to pivot the front edge of said dipper to said stick, a pulley pivoted on said dipper-stick, and a drag-line secured to the rear end of said dipper and passing over said pulley whereby the open end of the dipper is tipped downwardly to the work.

3. In an apparatus of the class described, a dipper-stick, lateral arms secured on said dipper-stick, a pulley in said stick; a dipper, means to hinge the front end of said dipper to one of said arms, and a drag-line secured to 75 the rear end of said dipper and passing over said pulley adapted to swing said dipper into contact with the other of said arms.

4. In an apparatus of the class described, a dipper-stick, means to impart longitudinal 80 movement to said dipper-stick, a pulley in said stick, means to lift the free end of said dipper-stick, a dipper, means to hinge the open end of said dipper to said dipper-stick, and a drag-line secured to the rear end of 85 said dipper and passing over said pulley adapted to draw said dipper toward the source of power.

In testimony whereof I affix my signature.

WARREN D. WILLIAMS.
